SOLE ATTACHING PRESS

Gotthold Strobel, Frankfort-on-the-Main,
GermanyApplication January 10, 1938, Serial No. 184,239
In Germany January 6, 1937

3 Claims. (Cl. 12—33)

This invention relates to a sole attaching press for shoes provided with a welt tensioning device.

According to the invention, sliding members displaceable in slots on the tensioning device possess smooth bores having internal threads the axis of which is disposed at an angle to the bore to enable threaded spindles supporting pressure segments to be movable within the sliding members in the axial direction of the smooth bore as well as of the threads.

By way of example, the invention is illustrated in the accompanying drawing, in which Figure 1 is a top view of the sole attaching press holding a shoe; Fig. 2, a front view thereof; Fig. 3, a detail view of a sliding member with spindle and detachable pressure segment; Fig. 4, a detail view of a sliding member with spindle in locked position; and Fig. 5, a view of a modification of the pressure unit comprising, besides the spindle and segment, a pressure equalizing spring.

Referring to the drawing, the tensioning frame or device 21 is guided with its parallel rectilinearly extending free ends 21a in holes 20 of the press member 1 supporting the last tensioning spindle 35 for the shoe 33 on the elastic pad 34 disposed underneath. In its semicircular portion the frame 21 is held in position by the eye 12 of a supporting member 13 on the lower portion of the press body 1. The frame 21 carries sliding members 22 provided with slots 23 for adjusting, i. e. removing and inclining, pressure segments 30. Each sliding member 22 has a smooth bore 24 wherein a spindle 25 for a pressure segment 30 can freely move. The spindle 25 is threaded over its entire circumference. Within the smooth bore 24 threads 29 are unilaterally cut in so that their axis forms an angle relative to the bore 24. By means of these threads 29 the threaded spindle 25 (Fig. 4) with its sliding member 22 can be locked like a screw joint while simultaneously the segment 30 engages the shoe 33. The spindle 25 is rotatably connected with the segment 30 and for this purpose provided at its conical end 32 with a recess 27 which holds an expanding spring 28. While permitting the attachment and withdrawal of

the segment 30 fitted with a hole corresponding to the diameter of the spindle 25 the spring 28 effectively prevents the segment 30 from accidentally dropping out of the end of the spindle 25.

Fig. 5 shows the interposition of a pressure equalizing spring 31 between the segment 30 and the conical end 32 of the spindle 25. When the spindle 25 is longitudinally displaced by hand, the spring 31 insures proper action of the segment 30 relative to the shoe 33 due to the smooth bore 24 of the sliding member 22, as shown in Fig. 4, without any lost motion on the part of the spindle 25.

I claim:—

1. A sole attaching press, comprising a last tensioning spindle, a semicircular welt tensioning frame disposed with its parallel and rectilinearly extending free ends in a hole of said spindle, threaded pressure spindles cooperating with freely rotatable segments for engaging the work, 20 slotted sliding members having a smooth bore and disposed on said tensioning frame for the reception of said pressure spindles and threads unilaterally cut into the smooth bore of the sliding members with their axis arranged at an angle 25 to the bore, said pressure spindles being longitudinally displaceable in the axial direction of said smooth bore and also screwable and lockable in the axial direction of the threads.

2. A sole attaching press according to claim 1, 30 wherein the pressure spindles have a conical recessed end for holding an expanding spring permitting attachment and withdrawal of the pressure segments and preventing them from accidentally dropping off of the spindle ends. 35

3. A sole attaching press according to claim 1, 40 wherein the pressure spindles have a conical recessed end for holding an expanding spring permitting attachment and withdrawal of the pressure segments and preventing them from accidentally dropping off of the spindle ends, where- 45 in a pressure equalizing spring is interposed between each pressure segment and the conical end of each pressure spindle.

GOTTHOLD STROBEL.
